UNITED STATES PATENT OFFICE.

JAMES F. DUGGAN, OF QUINCY, MASSACHUSETTS.

RAILWAY-SWITCH.

SPECIFICATION forming part of Letters Patent No. 406,036, dated July 2, 1889.

Application filed March 22, 1889. Serial No. 304,294. (No model.)

To all whom it may concern:

Be it known that I, JAMES F. DUGGAN, of Quincy, in the county of Norfolk, State of Massachusetts, have invented a certain new and useful Improvement in Railway-Switches, of which the following is a description sufficiently full, clear, and exact to enable any person skilled in the art or science to which said invention appertains to make and use the same, reference being had to the accompanying drawings, forming part of this specification, in which—

Figure 1 is a side elevation of a portion of a street-car, showing my improvement in use; and Fig. 2, a vertical transverse section taken on line $x-x$ in Fig. 1.

Like letters and figures of reference indicate corresponding parts in the different figures of the drawings.

My invention relates more especially to switches for street-railways; and it consists in certain novel features, as hereinafter fully set forth and claimed, the object being to produce a simpler, cheaper, and more effective device of this character than is now in ordinary use.

The nature and operation of the improvement will be readily understood by all conversant with such matters from the following explanation.

In the drawings, A represents the body of the car; B, the platform; C, the rails; D, the switch-plate, and E the switch-tongue. A switch-box G is sunken in the road-bed, the switch-plate D being disposed in the top b thereof. The plate D is provided with a transverse slot d , opening into the box G. A vertical rod f is secured to the free end of the tongue E and projects downward through said slot into said box. A vertically-arranged cam-lever H is pivoted at g within the box below the slot d , said lever being provided with a groove h in its upper end, in which the lower end of the rod f works. A horizontally-disposed lever K is pivoted at j in a vertical standard q , secured in the box, said lever being arranged at right angles to the rails C. The long arm l of the lever K is provided with a counterbalance-weight m , and in its outer end a roll p is journaled, said roll

working in the cam-grooves i k of the vertical lever H. A slot r is formed in the top b of the box adjacent to and parallel with the rail C opposite the switch-plate. A horizontally-arranged flat bar t is fitted to work vertically in the slot r , and is provided centrally with a downwardly-projecting arm v , in the lower end of which the end of the short arm w of the lever K is pivoted. A segment M is journaled on a bracket y , secured to the bottom 60 of the car A and in position to be forced into engagement with the bar t .

To the platform B of the car, below the dasher z , is pivoted a bell-crank lever 15. A horizontally-arranged rod 16 is pivoted by its 65 outer end to one arm of said lever, the inner end of said rod being pivoted to an arm 17, secured to the hub 18 of the segment M. To the opposite arm of the lever 15 a vertical rod 19 is pivoted and projects upward through 70 an opening in the car-platform. A transversely-arranged foot-lever 20 is pivoted by one end in standards 21 on the platform, the opposite end of said lever being pivoted to the upper end of the rod 19. A pin 22, secured to the lever 20, works vertically in an opening in the platform, and a coiled spring 23 is disposed around said spring and acts expansively to elevate the lever 20.

In the use of my improvement, when it is 80 desired to adjust the switch, the car-driver depresses the lever 20, causing the bell-crank lever 15 to draw the rod 16 outward and force the segmental wheel M downward into engagement with the bar t in the road-bed. Said bar 85 is thereby depressed and actuates the lever K, causing the roll p thereon to move upward from the position shown by dotted lines in Fig. 2, engaging the lever H in the grooves k i . Said lever H is thus forced backward and 90 carries with it the switch-tongue E. The bar t is of sufficient length to enable the segmental wheel to remain in engagement therewith until the car-wheel P has moved onto the switch-plate. As soon as the lever 20 is released by 95 the operator, the spring 23 will force it upward into its original position and elevate the wheel M, so that it will clear the road-bed, as shown by dotted lines in Fig. 1. When the wheel M frees the bar t , the weight m on the lever K 100

will again depress it and actuate the lever H to throw the switch-tongue into its original position.

Having thus explained my invention, what I claim is—

- 5 1. In a switch, the combination of a box in the road-bed, a switch-tongue, a rod projecting from said tongue into said box, a vertical cam-lever provided with a groove for said rod, a lever in said box provided with a roll for actuating said cam-lever, and a horizontal bar pivoted to said lever and adapted to be engaged by a projection on the car-body, substantially as described.
- 15 2. In a switch, the combination of a switch-box, a switch-tongue and transverse slot in the bed-plate, a rod on said tongue projecting through said slot into said box, a cam-lever in said box provided with a groove in which said rod works, a counterbalanced lever provided with a roll in engagement with said cam-lever, a horizontal bar pivoted to said counterbalanced lever and working in an opening in the top of the switch-box, and a segment pivoted on the car in position to be projected into said slot and engage said bar, substantially as described.
- 25 3. In a device of the character described, the combination of a spring-cushioned foot-lever on the car-platform, a bell-crank lever pivoted below said platform, a pivoted rod connecting said levers, a horizontal rod pivoted to said bell-crank lever, and a segment journaled on the car-body, whereby said wheel 30 may be projected into an opening in the road-bed and actuate a switch mechanism when said foot-lever is depressed, substantially as described.
- 35 4. In a device of the character described, a

horizontal bar working vertically in an opening in the switch-box in position to be engaged by a segment on the car-body, in combination with a roll-bearing counterbalanced lever pivoted to said bar, adapted to actuate a cam-lever connected with the switch-tongue, substantially as described.

40 5. In a device of the character described, the combination of a switch-box, a switch-tongue disposed thereon, a rod projecting from the switch-tongue into said box, a cam-lever for moving said tongue, a lever pivoted in said box and bearing a roll in engagement with said cam-lever, a horizontal bar working in an opening in said box and pivoted to said lever in position to be engaged by a projection on the car and move the switch-tongue, and a counterbalance-weight on said roll-lever for returning the same when said bar is released, substantially as described.

45 6. In a switch, the combination of the box G, the switch-plate D, having the tongue E and groove d, the rod f on said tongue, the cam-lever H, provided with the groove h, the lever K, having the weight m and roll p, and the bar t, working in the slot r and pivoted to said lever, substantially as described.

50 7. In a device of the character described, the combination of the car A, the segmental wheel M, journaled thereon and provided with the arm 17, the spring-cushioned lever 20, pivoted to the car-platform, the rod 19, bell-crank lever 15, and rod 16, all being arranged to operate substantially as described.

70 JAMES F. DUGGAN.
